UNITED STATES PATENT OFFICE.

DAVID G. McCAA, OF LANCASTER, PENNSYLVANIA, ASSIGNOR TO THE ELECTRIC APPARATUS CO., OF PARKESBURG, PENNSYLVANIA, A CORPORATION OF PENNSYLVANIA.

RADIO SYSTEM.

Application filed January 19, 1925. Serial No. 3,281.

My invention relates to the reception of high or radio frequency energy, without interference or disturbance due to other high or radio frequency energy produced artificially or by natural electricity as static atmospherics, etc., in systems in which the energy is transmitted either through the natural media or over a conductor or conductors extending between transmitting and receiving stations, for purposes of effecting at receiving stations controls, or signals which may be either telegraphic or telephonic.

In some of its aspects my present invention is of the character disclosed and claimed in my prior application Serial No. 722,246, filed June 25, 1924.

As in the aforesaid application, it is characteristic of my present invention that there is effected clear or sharp differentiation in the reception of signals between signals representing energy of low amplitude notwithstanding simultaneous existence of disturbing oscillations of high amplitude.

In accordance with my present invention, the frequency of the energy which it is desired should be excluded or reduced in effect and represented by oscillations set up by static or other natural electricity is caused to differ from, preferably to be lower than, the frequency of the energy which it is desired shall be received, and a signal-translating circuit, normally absorbing substantially no energy of either the desired or undesired oscillations, is caused to absorb energy of the desired oscillations and translate it into a control or signal in response to change in the natural period of the path or circuit which absorbs the energy from the natural media, such change in natural period being effected by energy of signal frequency derived from that part of the absorption path or circuit utilized in effecting change of its natural period.

Further in accordance with my invention, the energy of signal frequency so derived from the absorption path or circuit is amplified, more particularly by regenerative action of a thermionic tube, for effecting a change in the natural period of the absorption path or circuit.

Further in accordance with my invention, there are included in the absorption path or circuit inductances in parallel with

each other and preferably of materially different magnitudes, the inductance of lesser magnitude preferably utilized for coupling to the signal-translating circuit and the larger inductance comprising a pair of serially related inductances, preferably of different magnitudes, the smaller of said last named inductances coupled to the input circuit of a thermionic amplifier, preferably a regenerative amplifier, and the larger of said last named inductances coupled to the output circuit of said amplifier in such sense that the counter electro-motive-force of said larger inductance for signal frequency is changed, thereby changing the natural period of the absorption circuit or path; and more particularly, the sense of coupling of said larger inductance to the output circuit of the amplifier is in such sense for signal frequency less than static frequency that the magnitude of said larger inductance is decreased, or increased in case the signal frequency is higher than the static frequency.

Further in accordance with my invention, I provide in association with an inductive reactance a highly selective reactive system, as a regenerative amplifying system, for effecting with the inductive reactance a combination which with sharpness or high selectivity effects marked changes in the currents traversing the inductive reactance.

My invention resides in the method and apparatus of the character hereinafter described and claimed.

For an understanding of my method, and for an illustration of some of the various forms my apparatus may take, reference is to be had to the accompanying drawing, in which:

Fig. 1 is a diagrammatic view of radio receiving apparatus embodying my invention.

Fig. 2 is a diagrammatic view of a modified form of apparatus embodying my invention.

Referring to Fig. 1, A represents generically any absorption structure of a radio receiving system, either an open antenna path or, if desired, a closed circuit or loop, and broadly any circuit or path receiving energy directly from the natural media or more or less remotely coupled to such a circuit or path; and A may represent also a conductor

system extending between transmitting and receiving stations as utilized, for example, in high frequency or carrier wave conductor systems. For brevity, however, my invention will be described in connection with radio receiving systems utilized for any purposes, such as control of movements of ships or aircraft, of picture or motion picture apparatus, or signaling apparatus in general, including telegraphic and telephonic signals, it being understood that the translating instrument T, hereinafter referred to, represents generically any translating instrument, as a telephone or a control instrument of any character.

In the path between the antenna A and earth or counter-capacity E are included the variable tuning condenser C, which may be omitted if suitable or desirable, and the primaries P, P¹. The secondary S is oppositely inductively affected by the primaries P and P¹, whereby the circuit of the secondary S is not to any substantial degree affected by oscillations of any frequency simultaneously traversing the primaries P and P¹, when the switch s, in shunt to the primary P¹, is in open position indicated.

The secondary S is connected in the input or grid circuit of a thermionic tube V, which may be utilized either as the first stage of a series of radio frequency amplifiers, or, as indicated, as a detector. The tube V comprises the anode a, grid g, and cathode or filament f. In series with the secondary S is the variable inductance or variometer L, both shunted by the tuning condenser C¹, and between a terminal of the latter and the grid g is included the usual grid condenser K shunted by the grid leak resistance r. In the anode circuit is the source of current B and the signal-translating instrument T, which may be a telephone or any other control instrument, or which may be the primary of the first of one or more stages of audio frequency amplification.

As thus far described, the receiving circuit may be utilized for spark or wave train telegraphy or continuous wave telephony. However, if utilized for continuous wave telegraphy, there may be included in the grid circuit of the tube V a coil 1 inductively coupled to the coil 2 in circuit with the source of high frequency current w for well known heterodyne purposes.

In shunt to the primary P¹ are the serially related inductances or windings L¹ and P². The winding P² is coupled to the inductance L² in the input or grid circuit of the radio frequency amplifier tube V¹. The input circuit is tunable to the frequency of the oscillations representing the desired signal by the variable condenser C², or by varying L², or both. The connection of the input circuit to the cathode or filament f is

through the stabilizing resistance r¹ connected across the battery 4, which supplies current for the filament f. The positive side of the battery 4 or suitable terminal of the filament f is connected to earth or counter-capacity E. In the output or anode circuit is the source B¹, inductance L³, coupled to inductance L¹, and shunted by the variable condenser C³.

Preferably the magnitude of the inductance L¹, is great compared with the inductance P¹, and is also large with respect to the inductance P²; and preferably the magnitude of the inductance P² is much less than the magnitude of the inductance P¹.

With the switch s in closed position, thereby in effect cutting out the inductances P¹, L¹, and P² from the absorption or antenna circuit or path, the antenna path is tuned, as by adjusting the condenser C, to the frequency of the desired oscillations representing the desired signal or control. Or, in long wave systems, the condenser C may be in shunt to the two coils P and P¹, and when varied may be used to tune the absorption or antenna path to the frequency of the desired signal.

The circuit of the secondary S is similarly tuned to the frequency of the desired signal waves by varying the inductance L or condenser C¹, or both, the inductance of the secondary S and of L preferably greatly predominating over the capacity C¹ for effecting high selectivity to the desired frequency. The switch s is then opened, bringing into the absorption or antenna path or circuit the inductances L¹ and P² in series with each other and in shunt to P¹. Under these circumstances, due to the increased inductance in the antenna path, it is detuned with respect to the frequency of the desired oscillations or signal, and the frequency or predominant frequency of the oscillations set up in the antenna path by static, atmospheric or other disturbing electrical effects is lower than the frequency of the desired oscillations, and the decrement of the static or undesired oscillations is decreased because of the addition of inductance, and in consequence, oscillations of undesired frequency are more readily excluded from the circuit tuned to the frequency of the desired oscillations.

With the switch s open as aforesaid, both static and signal oscillations have substantially no effect upon the circuit of the secondary S, because of its reverse couplings to the primaries P and P¹, and there would be no effect upon the instrument T except for utilization of auxiliary means about to be described.

With the switch s open, which is the normal position for operation of the system, the reactance of the branch P¹ of the absorption circuit or path to both signal and static oscillations is materially or very much less

than the reactance of that branch containing the inductances L^1 and P^2 in series with each other. In consequence, the greater part of both the signal and static oscillatory energy flows through the branch P^1 and a far smaller portion through the branch L^1, P^2 .

It is desired, however, to increase the reactance of the branch L^1, P^2 for signal frequency to great degree, and to lesser degree for static frequency. This may be accomplished by in effect reducing the effective reactance of the inductance L^1 in its branch. This is accomplished by impressing upon the tuned input circuit of the tube V^1 oscillations of signal frequency traversing the coil P^2 . The tube V^1 , with its input and output circuits so coupled as to effect substantial degree of regenerative action, as by 15 the coupling effected by the capacity between the grid g and anode a , materially amplifies the oscillations of signal frequency impressed upon its input circuit, causing in its output circuit a highly amplified current of 20 signal frequency, the increased energy of amplification being derived from the source B^1 . The highly amplified oscillations of signal frequency then inductively affect the coil L^1 , which is coupled in such sense to L^3 that the counter electro-motive-force of the coil L^1 for signal frequency is substantially 25 completely annulled, though it is not completely annulled for static frequency, particularly due to difference in amplitude between the strong static and weak signal 30 oscillations. Upon such decrease of reactance of L^1 for signal frequency, the amplitude of the oscillations of signal frequency in the branch L^1, P^2 has now increased, 35 correspondingly diminishing the amplitude of energy of signal frequency in the coil P^1 , with the result that the secondary S is now predominatingly influenced by signal 40 frequency by the primary P , though the effect upon the secondary S by static oscillations in the primaries P, P^1 still remains more nearly equal, with the result that in 45 the signal-translating circuit, enhanced by the tuning of the input circuit of the tube V , signal energy greatly predominates over static energy, with the result that in the translating instrument T weak energy is readily distinguished notwithstanding the 50 existence of relatively strong static. The inductive effect at signal frequency of the coil L^3 upon coil L^1 does not materially or so largely decrease the reactance or counter 55 electro-motive-force of the coil L^1 with respect to the different or static frequency, and therefore the static energy in the coil P^1 remains more nearly what it was originally.

It is interesting to observe that that setting of the condenser C which tunes the absorption path to the signal frequency when switch s is closed also serves to tune the

absorption path to signal frequency when the switch s is open and the coil L^3 is inductively influencing the coil L^1 at signal frequency.

The aforesaid annulment or great decrease of reactance of the coil L^1 for signal frequency, as effected by the amplified signal frequency in the coil L^3 , has the effect to leave the relatively small inductance P^2 in parallel with the primary P^1 , thereby in effect largely robbing the coil P^1 of current of signal frequency, much the same as if the switch s were closed. Furthermore, there is a cumulative action in the sense that as the reactance of L^1 decreases for signal frequency, current of signal frequency in P^2 increases in amplitude, causing relatively further or increased amplification by the tube V^1 and increased inductive effect of L^3 upon L^1 , until a substantially saturated or stable state is attained.

In case it is desired that the frequency of the static oscillations shall be higher than the signal frequency, with the switch s open the antenna or absorption path is tuned to a frequency higher than the signal frequency. In this case the switch s is left open during the operation of the system. However, the sense of coupling of L^1 to L^3 is reversed in this case, with the result that the reactance of L^1 as influenced by L^3 at signal frequency is materially increased, the sense of coupling of P^2 to L^2 remaining as it was in the first case described. Because of the increase of reactance of L^1 at signal frequency, greater energy of signal frequency is forced to traverse the coil P^1 , which coil in this instance at signal frequency predominates over P in influencing S and the signal-translating circuit.

In the case where the signal frequency is higher than the static frequency, in which case the reactance of L^1 at signal frequency is to be annulled, there are two paths through which energy of signal frequency may reach the input circuit of the tube V^1 . One of these paths is through the coupling L^1, L^3 through the capacity between anode and grid of the tube V^1 , and the other is through the coupling P^2, L^2 , the latter coupling opposing the effect of the coupling L^1, L^3 . In the second case, where the signal frequency is lower than the static frequency, and the reactance of winding L^1 is to be increased, the coupling L^1, L^3 assists the coupling P^2, L^2 in transferring energy of signal frequency to the input circuit of the tube V^1 . In both cases it is preferred that the coupling between L^1 and L^3 be loose, while the coupling between P^2 and L^2 may be either loose or close, but preferably close.

The arrangement of Fig. 2 is generically the same as that of Fig. 1. However, in shunt to the coil P^1 is utilized the coil L^1 inductively coupled to the coil L^3 , a portion

of which is in the anode circuit and another portion of which is in the input circuit of the regenerative radio frequency amplifier V¹. Again, the energy of signal frequency appearing in L¹ is regeneratively amplified in the tube V¹ and reacts upon L¹ to decrease or annul its reactance at signal frequency in the case where the signal frequency is higher than static frequency. In case the signal frequency is lower than the static frequency, the sense of coupling of L¹ to L³ is reversed, so that the reactance of L¹ at signal frequency is increased.

In the arrangements of both Figs. 1 and 2 above described, the amplification, and particularly the regenerative amplification, of the signal energy as effected by the tube V¹, effects high selectivity of the signal frequency in the branch L¹, P² of Fig. 1, or in the branch L¹ of Fig. 2. This high selectivity effects a highly selective low reactance system for the signal frequency in shunt, which system is in shunt to the coil P¹.

For the sake of brevity in the appended claims, the term "signal" is employed generically to include signals of any character, including telegraphic and telephonic signals, and any other analogous effect, including controls; and the term "static" is generally employed to include static and other natural electrical effects and also other effects having artificial origin such as are caused or represented by waves or oscillations other than those representing the desired signal or control.

What I claim is:

1. In the reception of radio signals, the method which comprises receiving the signal energy in a path including inductances and having a natural period differing from the period of the received oscillations, and changing the natural period of said path by dividing the energy of oscillations between said inductances in said path, and changing the reactive effect of one of said inductances by amplifying the oscillation energy traversing said one of said inductances.

2. In the reception of radio signals, the method which comprises receiving the signal energy in a path including inductances and having a natural period differing from the period of the received oscillations, and changing the natural period of said path by dividing the energy of oscillations between said inductances in said path, and changing the reactive effect of one of said inductances by regeneratively amplifying the oscillation energy traversing said one of said inductances.

3. In the reception of radio signals in a system comprising a path for receiving the signal energy, said path having branches including, respectively, inductance and a plurality of inductances, said path having a natural period differing from the period of the

received oscillations, the method which comprises changing the natural period of said path by dividing the oscillation energy between said branches, amplifying the oscillation energy traversing one of the inductances of one of said branches, and impressing the amplified energy upon the other inductance of said one of said branches.

4. In the reception of radio signals in a system comprising a path for receiving the signal energy, said path having branches including, respectively, inductance and a plurality of inductances, said path having a natural period differing from the period of the received oscillations, the method which comprises changing the natural period of said path by dividing the oscillation energy between said branches, regeneratively amplifying the oscillation energy traversing one of the inductances of one of said branches, and impressing the amplified energy upon the other inductance of said one of said branches.

5. In the reception of radio signals in a system comprising a path for receiving the signal energy, said path having in series therein inductances in parallel with each other, the method which comprises amplifying the signal oscillations traversing one of said inductances, and reducing the reactive effect of said one of said inductances by the amplified oscillations, and thereby decreasing the amount of signal energy in the other of said inductances.

6. In the reception of radio signals in a system comprising a path for receiving the signal energy, said path having in series therein inductances in parallel with each other, the method which comprises regeneratively amplifying the signal oscillations traversing one of said inductances, and reducing the reactive effect of said one of said inductances by the amplified oscillations, and thereby decreasing the amount of signal energy in the other of said inductances.

7. For the reduction of the effect of static in the reception of signals in a system comprising a receiving path having a natural period differing from the period of the signal oscillations, said path including inductances, and a signal circuit normally subjected equally and oppositely to the signal and static oscillations, the method which comprises dividing the signal energy between said inductances, subjecting said signal circuit to the oscillations traversing one of said inductances, and amplifying the signal energy in another of said inductances to decrease its reactance to the signal energy.

8. The method of changing the relative magnitudes of alternating current energy traversing inductances in parallel with each other, which comprises amplifying the energy in one of said inductances to change its reactance to said energy.

9. The method of changing the relative magnitudes of alternating current energy traversing inductances in parallel with each other, which comprises regeneratively amplifying the energy in one of said inductances to change its reactance to said energy.

10. The combination with a path having inductances in parallel therein, of means for amplifying the energy traversing one of said inductances to vary its reactance to said energy.

11. The combination with a path having inductances in parallel therein, of means for selectively amplifying the energy traversing one of said inductances to vary its reactance to said energy.

12. The combination with a path having inductances in parallel therein, of means for regeneratively amplifying the energy traversing one of said inductances to vary its reactance to said energy.

13. A receiving system comprising a path traversed by signal and static oscillations and having a natural period differing from the period of the signal oscillations, a plurality of inductances in parallel with each other in said path, a signal circuit influenced by one of said inductances, and means for amplifying the energy in another of said inductances to change its reactance to said energy.

14. A receiving system comprising a path traversed by signal and static oscillations and having a natural period differing from the period of the signal oscillations, a plurality of inductances in parallel with each other in said path, a signal circuit influenced by one of said inductances, and means for regeneratively amplifying the energy in another of said inductances to change its reactance to said energy.

15. A receiving system comprising a path traversed by signal and static oscillations and having a natural period differing from the period of the signal oscillations, an inductance in said path, a signal-translating circuit influenced by said inductance, a plurality of inductances between which and said first named inductance signal energy divides, and regenerative amplifying means comprising input and output circuits inductively related, respectively, to said plurality of inductances.

16. A receiving system comprising a path traversed by signal and static oscillations and having a natural period differing from the period of the signal oscillations, a signal-translating circuit, inductances in said path normally equally and oppositely influencing said circuit when said inductances are traversed by signal and static oscillations, and means for changing the ratio of the influences of static and signal oscillations

upon said circuit comprising an inductance between which and one of said first named inductances oscillatory energy divides, and means for amplifying the energy traversing said last named inductance for effecting a change of its reactance to the energy traversing it.

17. A receiving system comprising a path traversed by signal and static oscillations and having a natural period differing from the period of the signal oscillations, a signal-translating circuit, inductances in said path normally equally and oppositely influencing said circuit when said inductances are traversed by signal and static oscillations, and means for changing the ratio of the influences of static and signal oscillations upon said circuit comprising an inductance between which and one of said first named inductances oscillatory energy divides, and means for regeneratively amplifying the energy traversing said last named inductance for effecting a change of its reactance to the energy traversing it.

18. A radio receiving system comprising a path traversed by signal and static oscillations and having a natural period differing from the period of the signal oscillations, said path including branches, inductances in said branches, and means for changing the natural period of said path comprising means for changing the combined reactance of said inductances in said branches, said means comprising means for amplifying the oscillation energy traversing one of said inductances, and means for impressing the amplified energy upon that branch including said one of said inductances.

19. A radio receiving system comprising a path traversed by signal and static oscillations and having a natural period differing from the period of the signal oscillations, a signal-translating circuit, a coupling for impressing signal and static oscillations upon said signal-translating circuit, a magnetic coupling comprising an inductance for impressing signal and static oscillations upon said signal-translating circuit in opposition to said first named coupling, and means for changing the ratio of the energies impressed upon said signal-translating circuit by said couplings comprising a branch path between which and said inductance the received oscillatory energy divides, and means for

changing the reactance of said branch, said last named means comprising means for amplifying the oscillatory energy in said branch, and means for impressing the amplified oscillatory energy upon said branch.

In testimony whereof I have hereunto affixed my signature this 13th day of January, 1925.

DAVID G. McCAA.
